(57) CLAIM

The ornamental design for a table showing Illinois college logo, as shown and described.

DESCRIPTION

FIG. 1 is a perspective view of a first embodiment of the table showing Illinois college logo.

FIG. 2 is a perspective view of a second embodiment of the table where the table has an elevated lip.

FIG. 3 is a top view of the first embodiment.

FIG. 4 is a side view of the first and second embodiments of the table.

FIG. 5 is an end view thereof.

FIG. 6 is a bottom view thereof; and,

FIG. 7 is a top view of the second embodiment.

The word "ILLINOIS" forming part of the claimed design is a registered trademark of the University of Illinois.

The broken lines are for environmental purposes only and form no part of the claimed design.
